SPRAY NOZZLE

Selwyne P. Kinney, Crafton, Cornelius J. Garigan, Greentree, and Ward W. Clarke, Monaca, Pa., assignors to S. P. Kinney Engineers, Inc., Pittsburgh, Pa., a corporation of Pennsylvania

Application November 14, 1949, Serial No. 127,216

3 Claims. (Cl. 299—117)

1

This invention relates to spray nozzles, and, more particularly, to an improved spray nozzle of the self-cleaning or flushing type which may be used in blast furnace gas washers.

Spray nozzles used in blast furnace gas washers operate under adverse conditions in that the water supply to the nozzle is frequently very dirty. These nozzles are constructed to furnish a solid cone spray. For this purpose, the nozzles are commonly provided with turbulent condition producing deflecting elements spaced inwardly from the nozzle orifice. These deflecting elements may take the form of a pair of crossed semi-circular blades arranged to provide a tortuous path for the water flowing to the orifice. Due to the dirty condition of the water, dirt, fiber, weeds, string, etc., and other foreign material collects against the cross blades. This material will build up on the cross blades until plugging, partial or complete, of the nozzle is had. The plugging action takes place regardless of the shape or construction of the turbulent condition producing deflecting blades in the nozzle.

One of the principal objects of this invention is to provide a spray nozzle for producing a solid cone spray for use in blast furnace gas washers which may be flushed or cleaned by operation of a remotely located control element without the necessity of taking the nozzle apart. To this end, the crossed blades or deflecting elements are mounted for movement from their operative spray producing position in the nozzle to a withdrawn position which is also within the nozzle for a cleaning or flushing operation. The spray water is supplied to the nozzle by a supply conduit which is angularly inclined with respect to the axis of the spray nozzle. The withdrawn position of the crossed blades or deflecting elements is at the point of intersection of the axes of the spray nozzle and its supply conduit. When the crossed blades are withdrawn to this position, the relative direction of movement of the water over the crossed blades will be changed with respect to the direction of water movement over the blades when they are in their operative spray producing position. Due to the change in the direction of movement of the water over the blades, dirt which has built up on the cross blades will be flushed off and washed out through the spray nozzle. Such dirt may move out through the nozzle without interference since the withdrawal of the crossed blades provides an unobstructed passage for the water through the nozzle.

Another object of the invention is to provide a

2

linkage system which may be positively actuated from a remote point for moving the crossed blades or deflecting elements of the nozzle to a withdrawn position for a cleaning or flushing action thereon.

A still further object of the invention is to provide a mounting for the deflector elements of a spray nozzle by which they may be moved to a withdrawn position still in the path of the water flowing through the nozzle in which the flow of water through the nozzle will be effective to perform a cleaning action on the deflector elements.

Other objects and advantages of the invention will become apparent from the following description.

In the drawings, there is shown a preferred embodiment of the invention. In this showing:

Fig. 1 is a sectional view of a spray nozzle constructed in accordance with the principles of this invention;

Fig. 2 is an end elevational view of the nozzle looking in a direction from the right of Fig. 1; and

Fig. 3 is a sectional view taken substantially along the line III—III of Fig. 1.

Referring to the drawings, the numeral 1 designates a spray nozzle having a circular discharge orifice 2 therein. The body of the nozzle 1 is enlarged inwardly of the orifice 2 to provide a cylindrical chamber 3 in which deflector elements 4 and 5 are mounted. The deflector elements 4 and 5 are semi-circular discs arranged in opposed and crossed fashion as illustrated. The water flowing through the nozzle 1 strikes the discs 4 and 5, and in order to continue its flow through the nozzle, must flow laterally to a position underneath the disc other than the one obstructing its flow. This imparts a swirling turbulent motion to the water flowing to the orifice 2.

Consequently, the water emerging from the orifice 2 will be in the form of a fine spray and will spread out in the shape of a solid cone. Although the nozzle has been described as having semi-circular discs therein, it will be understood

that the invention is equally applicable to nozzles having other forms of turbulent deflector elements operative to cause a solid cone-shaped spray to be formed by the water emerging from the orifice 2.

With nozzles of this type, dirt in the spray water may collect on the deflector elements 4 and 5, and cause complete or partial clogging of the spray nozzle. The collection of dirt on the deflector elements is accelerated where the water contains elongated pieces of foreign material such

as string, weeds, or fibrous materials. In a manner to be described, this invention provides apparatus which enables the water flowing through the nozzle to remove dirt which may have collected on the spray producing part.

Before referring to the structure with which this invention is primarily concerned, attention is directed to the fact that the structure of the elements 3 and 4 specifically shown forms the subject matter of an invention covered in the copending application of Selwyne P. Kinney, Serial No 129,083, November 23, 1949, to which reference is hereby made for a more detailed description and a better understanding. The novel structure comprises the angularly inclined blade elements 4a and 5a respectively positioned under the blade elements 5 and 4 in angular positions parallel to the blades 5 and 4. The blade element 4a has an arm 4b which is welded to the upper surface of the blade element 4 to secure it in position, and the blade element 5a similarly has an arm 5b which is welded to the upper surface of the blade element 5 to secure it in position. In addition, the edges 4c and 5c are spaced a slight distance apart so that a limited amount of water may flow through the nozzle without striking the blades 4 and 5. This specific structure has been found to decrease the tendency for dirt to collect in the nozzles with consequent plugging, and to increase the size of the cone of spray emerging from the nozzle. In action, water striking the element 4 is deflected laterally to a position under the element 5 where it is again deflected by the element 4a. In a similar manner, a second deflecting action is performed by the blade element 5a on the water flowing laterally to a position under the element 4. The deflecting actions accomplished by the elements 4a and 5a is effective to increase the diameter of the cone of spray emerging from the nozzle.

In accordance with the principles of this invention, a conduit or housing 6 is provided for supplying water to the nozzle 1. The conduit housing 6 is threaded as at 7 for connection to a water supply conduit. As will be noted from Fig. 1, the axis of the conduit 6 is in a horizontal plane and is angularly inclined with respect to the axis of the nozzle 1. The axes of the nozzle 1 and conduit 6 intersect at the point 8, and the housing 6 is enlarged about this point to provide a cleaning chamber into which the deflecting elements may be withdrawn to a position as indicated by the dotted lines.

The nozzle 1 is provided with a flange 9 at its upper end which is receivable in a groove 10 formed in a circular opening in the housing 6. The flange 9 is held against the bottom of the groove 10 by a circular sealing ring 11 which is clamped into position by a clamping ring 12 secured to the housing 6 by fastening elements 13.

In order to remove the deflector elements 4 and 5 to their withdrawn position, they are rigidly secured, as by welding, to the lower end of an operating rod 14 which is mounted for rectilinear movement along an extension of the axis of the nozzle 1. The rod 14 has a guided sliding movement through a liquid sealing gland 15 mounted in an opening formed in a plate 16 which provides a top cover for the housing 6. The upper end of the rod 14 has a threaded connection to a bifurcated member 17 having spaced arms 18 which form a support for a pin 19 extending transversely of the arms 18. A bell crank lever 20 having a pivot support 21 is provided for imparting movement to the rod 14. One arm of the bell crank lever is provided with a slot 22 in which

the pin 19 is receivable. The other arm of the bell crank lever 20 is provided with an opening for the reception of a pin 23 extending transversely of the arms 24 of an actuating yoke which has threaded connection with the inner end of the actuating rod 25. The actuating parts for the rod 14 are contained within a housing 26 mounted on the cover plate 16. The actuating rod 25 is slideably mounted in the housing 26 by a stuffing gland 27. The housing 26 is preferably filled with oil or grease to protect the actuating parts from the effect of dirt and water. A stopper 28 is provided in the housing 26 by which it may be filled with oil, grease, or other suitable lubricant.

In operation, the nozzle is coupled to a water supply pipe in a blast furnace gas washing apparatus by the threaded coupling 7. The water is then fed to the orifice 2 through the housing 6 and chamber 3. As explained above, the turbulent condition imparted to the water as it flows by the deflecting elements 4 and 5 will cause the water to emerge from the nozzle 2 in a dense spray having the shape of a solid cone. When dirt has collected on the deflector plates 4 and 5 or other surfaces of the nozzle, a flushing action may be had by moving the rod 25 to the right as viewed in Fig. 1 to move the bell crank lever 20 to the position shown in dotted lines. Such movement will pull the operating rod 14 upwardly to move the deflecting elements 4 and 5 to the position shown in dotted lines. When the deflecting elements 4 and 5 are withdrawn from their operative position in the nozzle 1 to the flushing position as indicated by dotted lines, the direction of movement of the water over the surface of the deflecting elements 4 and 5 will have been changed. Whereas the water moves over the deflector elements in a substantially vertically downward direction when they are in their operative position in the chamber 3, the water striking the deflector elements when in their flushing position will be traveling in a horizontal direction. The water will thus strike the deflector elements at a different angle when they are in their withdrawn flushing position and will be effective to knock off any dirt which may have accumulated on such elements. Such dirt may then flow readily out through the nozzle 2 since the movement of the water through the nozzle will not be impeded when the deflector elements are in their flushing position.

After the nozzle has been flushed, the deflector elements 4 and 5 may be moved to their operative position in the chamber 3 by moving the actuating rod 25 inwardly to the left as viewed in Fig. 1. This will rotate the bell crank lever 20 in a counter-clockwise direction to move the rod 14 downwardly for returning the deflector elements 4 and 5 to their operative positions as illustrated in Fig. 1.

It will be understood that the principles of this invention are applicable to nozzles in which the deflector elements 4a and 5a are omitted. That is, any type of deflector element may be provided in the nozzle 1 for the purposes of this invention.

The actuating rod 25 will, of course, extend to a position out of the housing (not shown) constituting a part of the gas washing apparatus in which the nozzle is mounted. In such case, the flushing action of the nozzle which may be accomplished by a manual operation of the rod 25. However, it will be understood that automatic or power actuation of the rod 25 is contemplated in accordance with the principles of this invention.

tion. Where power means is provided for actuating the rod 25, the power means, such as a solenoid, for example, may be remotely located in a position outside of the housing for the apparatus, or may be located within the housing in a position adjacent the nozzle housing 26. In such case, it will be understood that actuation of the rod 25 may be made automatically at timed intervals or in response to clogging of the nozzle 1.

While we have illustrated and described one specific embodiment of our invention, it will be understood that this is merely by way of illustration, and that various changes and modifications may be made therein within the contemplation of our invention and under the scope of the following claims.

We claim:

1. A spray nozzle for gas washing apparatus comprising a body member having an end portion of reduced diameter with a discharge orifice therein, an enlarged portion inwardly of said orifice and forming a cylindrical chamber, and a tapering portion connecting said chamber with said orifice, said tapering, end, and enlarged portions having a common axis, a housing connected with said body member and providing an enlarged flushing chamber inwardly of said cylindrical chamber, a conduit for supplying water to said flushing chamber for delivery to said orifice, said conduit having its axis inclined relative to and intersecting with said common axis in said flushing chamber, deflector vanes having a normal operative position in said cylindrical chamber for causing water flowing therethrough to emerge from said orifice in a spray having the shape of a solid cone, said deflector vanes having a mounting for movement from said operative position in said cylindrical chamber to a flushing position in said flushing chamber adjacent the point of intersection of said axes, and an actuating member for moving said mounting and thereby said vanes from said operative position to said flushing position in which water entering the flushing chamber will impinge directly on said vanes and thereby remove debris lodged thereon.

2. A spray nozzle for gas washing apparatus comprising a body member having an end portion of reduced diameter with a discharge orifice therein, an enlarged portion inwardly of said orifice and forming a cylindrical chamber, and a tapering portion connecting said chamber with said orifice, said tapering, end, and enlarged portions having a common axis, a housing connected with said body member and providing an enlarged flushing chamber inwardly of said cylindrical chamber, a conduit for supplying water to said flushing chamber for delivery to said orifice, said conduit having its axis inclined relative to and intersecting with said common axis in said flushing chamber, deflector vanes having a normal op-

erative position in said cylindrical chamber for causing water flowing therethrough to emerge from said orifice in a spray having the shape of a solid cone, a rod mounting said vanes and having a portion thereof extending to a position without said housing, and means including a connection for actuating said rod from a remote location to move said vanes axially from said operative position to a flushing position in said flushing chamber adjacent the point of intersection of said axes.

3. A spray nozzle for gas washing apparatus comprising a body member having an end portion of reduced diameter with a discharge orifice therein, an enlarged portion inwardly of said orifice and forming a cylindrical chamber, and a tapering portion connecting said chamber with said orifice, said tapering, end, and enlarged portions having a common axis, a housing connected with said body member and providing an enlarged flushing chamber inwardly of said cylindrical chamber, a conduit for supplying water to said flushing chamber for delivery to said orifice, said conduit having its axis inclined relative to and intersecting with said common axis in said flushing chamber, deflector vanes having a normal operative position in said cylindrical chamber for causing water flowing therethrough to emerge from said orifice in a spray having the shape of a solid cone, an enclosure mounted on said housing, an operating rod having opposite ends positioned respectively in said housing and enclosure and being mounted for rectilinear movement, said vanes being mounted on the end of said rod within said housing for movement thereby from said operative position to a flushing position in said flushing chamber, and means for operating said rod comprising an actuating rod extending into said enclosure, and a bell crank mounted in said enclosure and having one arm connected to said actuating rod and its other arm connected to said operating rod.
